ACCORDION GRILL

David P. Biasco, Lincolnwood, Ill., assignor to Accordion Manufacturers and Wholesalers Outlet, Inc., Chicago, Ill., a corporation of Illinois

Application October 10, 1957, Serial No. 48,054

Term of patent 7 years

(Cl. D56—1)

Fig. 1

The dotted line disclosure appearing in Figure 1 of the drawing is for illustrative purposes only.

I claim:

The ornamental design for an accordion grill, substantially as shown and described.
